UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed August 31, 1923. Serial No. 660,284.

To all whom it may concern:

Be it known that I, WALTER P. ALBERT, a citizen of the United States of America, residing at East Orange, in the county of Essex and State of New Jersey, have invented certain new and useful Improvements in Telephone Systems, of which the following is a full, clear, concise, and exact description.

10 This invention relates to telephone systems.

In a telephone system wherein trunk circuits are employed between a main exchange and a private branch exchange, it is necessary that metering mechanism be provided for the purpose of counting the number of calls outgoing from the private branch exchange so that a charge may be made therefor.

20 Heretofore the counting of such outgoing calls has been accomplished through the manual operation of a contact by the attendant at the private branch exchange.

Such a method of counting the calls is 25 unreliable as the attendant may fail to count some calls or the counter so operated may indicate more calls than have actually been made.

It is an object of this invention therefore 30 to provide a telephone system wherein the calls outgoing over a trunk circuit from a private branch exchange are automatically registered by a metering device.

Since the calls incoming to the private 35 branch exchange should not be registered, the operation of the metering device on incoming calls must be prevented.

Another object of the invention therefore 40 is to render the metering device effective to register calls, on a two-way trunk circuit, in one direction only.

This object is attained by the provision 45 of means in a trunk circuit which discriminates between calls incoming to, and outgoing from a telephone exchange to selectively operate a message registering device.

Another feature of the invention resides 50 in the provision of means for preventing the false operation of the message registering device.

The above and other features of this invention will readily appear from the following detailed description made with refer-

ence to the accompanying drawings, in which Fig. 1 shows a common battery station A and a private branch exchange attendant's cord circuit; and Fig. 2 shows a trunk circuit embodying the features of the invention, automatic switches schematically represented at S and C and a machine switching subscriber's line B. In reading the drawings, Fig. 1 is placed to the left of Fig. 2.

A call originating at station A will be traced to the station B, the connection including the private branch exchange attendant's cord circuit, the trunk circuit L, selector S and connector C.

A subscriber at A, to initiate a call removes the receiver from the switchhook, thereby causing the energization of line relay 10 which in turn causes the lighting of line lamp 12.

The private branch exchange attendant observing the illumination of the line lamp 12 inserts plug P' of an idle cord circuit into the jack J' in which the subscriber's line, corresponding to the lamp 12, terminates. The insertion of plug P' into jack J' causes the operation of supervisory relay 14. Relay 14 in operating, prevents the illumination of supervisory lamp 16 at this time. The insertion of plug P' into jack J' closes the local contact 25 of jack J' whereupon cut-off relay 11 operates to disconnect line relay 10 from the line circuit and to connect ground to the sleeve contact of jack J'. Supervisory lamp 17 is thereupon lighted over a circuit from grounded battery through lamp 17, contact of supervisory relay 16, sleeve contacts of plug P' and jack J' and contact of cut-off relay 11 to ground. The lamp 17 lighting at this time serves as a guard signal.

The attendant then actuates the talking key 13, thereby bridging the operator's telephone set across the tip and ring conductors of the cord so that she may now converse with the calling subscriber to ascertain the nature of the desired connection. Upon learning that a connection with the automatic subscriber at station B is desired, the attendant tests for an idle trunk in the well known manner.

Assuming that trunk L is the first idle 105 trunk encountered, the attendant inserts

plug P^2 into jack J^2 of the idle trunk L . When the plug P^2 is fully inserted in jack J^2 , supervisory relay 16 operates over a circuit from grounded battery through the lower right hand winding of repeating coil 15, winding of supervisory relay 16, lower normal contacts of ringing key 18, ring contacts of plug P^2 and jack J^2 , lower left hand winding of repeating coil 100, bridging element 101, upper left hand winding of repeating coil 100, tip contacts of jack J^2 and plug P^2 , upper normal contacts of ringing key 18, to ground through the upper right hand winding of repeating coil 15. Relay 16 in operating opens the circuit of and extinguishes lamp 17.

When plug P^2 is inserted into jack J^2 , the normally closed contacts of the jack are opened, thereby removing the ringing relay 130 from across the tip and ring conductors of the trunk. When the alternate contact 102 of jack J^2 is closed, slow releasing relay 104 operates. The closure of the contact 106 of jack J^2 connects a holding bridge including the winding of polarized relay 107, resistance element 108, and conductors 109 and 110 across the central office side of the repeating coil 100.

The attendant now actuates the dial key 111 associated with the trunk L , thereby transferring the holding of the central office from the bridge above traced to the contacts 112 of the dial D. The attendant now actuates the dial D to dial the desired central office number in the usual manner and then restores the dial key 111. As a consequence of the operation of the dial D, the selector and connector, schematically represented at S and C, respectively, function in a manner well known in the art and as described in detail in reissue patent to Newforth No. 13,901, dated April 13, 1915 to connect the terminals of the trunk L to the terminals of the called line. It is believed unnecessary to enter into a detailed description of these switches and their operations, since they do not enter into the present invention. For the complete disclosure of such switches, reference may be had to the above mentioned patent.

The restoration of the dial key 111 again closes the holding bridge, including the winding of polarized relay 107 and resistance element 108, across the central office side of the repeating coil 100 to hold the central office switches operated.

It will now be assumed that the connection to the subscriber's line B is completed and that the subscriber has been signaled in the well known manner and as shown in the above mentioned patent.

In response to the signal, the subscriber at station B removes the receiver from the switchhook, thereby causing relay 113 to operate in a circuit including the subscrib-

er's line loop. Relay 113 in attracting its armatures, interchanges the tip and ring connections of relay 114, thereby reversing the current over the trunk conductors and through the winding of polarized relay 107. 70 This reversal of current causes the operation of polarized relay 107 whereupon relay 115 operates and then locks up in a circuit including the normal contact of relay 119 and the alternate contact of relay 104. The 75 operation of relay 115 completes through its right hand contact an operating circuit for the register magnet 117.

The magnet 117 in operating, causes the register 118 to function in a manner well known in the art to register the outgoing call. When the register magnet 117 operates, it closes its left hand contact, causing relay 119 to operate. Relay 119 in attracting its right hand armature opens the locking circuit for relay 115, and locks itself to ground on the alternate contact of relay 104. Relay 115 thereupon releases, causing the release of the register 118. At its outer left hand contact, relay 119 short circuits the polarized relay 107, thereby preventing this relay from again operating to cause the false operation of the register 118 which may be effected by the called subscriber actuating the receiver switchhook in answering a call. It will be noted that by the attraction of the inner left hand armatures of relay 119, polarized relay 120 is connected across the central office side of repeating coil 100, but being short circuited by contact 106 of jack J^2 this relay does not operate at this time.

For the sake of simplicity, it will be assumed that the period of conversation has ended and that the calling subscriber has replaced the receiver on the switchhook, thereby opening the circuit for supervisory relay 14 and causing supervisory lamp 16 to light over the sleeve circuit. Upon noting this signal, the attendant proceeds to take down the connection, and it will be assumed that the plug P^2 is removed from jack J^2 before the called subscriber at station B has restored the receiver. The contacts 106 and 102 of jack J^2 are so adjusted that contact 106 is opened before contact 102, when the plug P^2 is withdrawn from the jack J^2 , so that the short circuit about the polarized relay 120 is removed before the circuit for relay 104 is opened. Relay 104 is made slow to release to further insure the operation of relay 120 before its own release, thereby maintaining relay 119 operated. Relay 120 now operates on reversed battery from the selector S due to the fact that relay 113 is still operated and in attracting its armature establishes a locking circuit for relay 119 independent of relay 104, so that when the latter relay deenergizes as a result of the opening of the jack contacts 130

102, relay 119 will remain energized to hold polarized relay 107 short circuited until the called subscriber restores the receiver to the switchhook and again reverses the current over the trunk. This arrangement prevents a double registration which might occur if the attendant reinserted plug P^2 into jack J^2 before the called party at station B replaced the receiver on the switchhook at the termination of a call. The locking up of relay 115 before the register 118 operates as hereinbefore described, prevents double registration should the called subscriber send out a preliminary pulse in removing the receiver from the switchhook in answer to a call.

Should the called subscriber replace the receiver on the switchhook before the attendant withdraws plug P^2 from jack J^2 relay 120 would not operate.

When the operator withdraws plug P^2 from the jack J^2 and the subscriber at B has replaced the receiver on the switchhook, relays 104 and 120 will release. Relay 120 in restoring, opens the locking circuit for relay 119, whereupon this relay retracts its armatures and restores the circuit to normal. The release of the automatic switches is accomplished in the same manner as described in the above mentioned patent. When the attendant withdraws plug P' from jack J' , the circuit for cut-off relay 11 is opened, whereupon this relay releases and in retracting its armatures again connects the line relay 10 to the tip and ring conductors of the subscriber's line A, thereby conditioning the line for a new call. The circuits are now in normal condition, relay 14 having restored when the calling subscriber replaced the receiver on the switchhook at station A, and relay 16 being deenergized when the plug P^2 was withdrawn from jack J^2 .

On a call originating at the automatic station B, the automatic switches will function in the manner described in the above mentioned patent to seize an idle trunk L, whereupon ringing current is automatically connected to the trunk and passes through the repeating coil 100 to cause the operation of relay 130, which is bridged across the trunk by way of the normally closed contacts of jack J^2 . Relay 130 in operating, causes the operation of slow-to-release relay 132. The operation of relay 132 causes the operation of relay 131 over a circuit including the alternate contact of relay 132 and the contact of relay 130. Relay 131 is slow to operate so as to permit relay 132 to be completely energized before relay 131 operates. Relay 131 in attracting its right hand armature, opens the energizing circuit for relay 132 which, after a short interval of time releases. Relay 131 in operating locks up over a circuit including the right hand

normal contact of relay 132, left hand alternate contact of relay 131 and the normal contact of relay 104. Relay 130 remains operated so long as ringing current is connected to the trunk the ringing current being disconnected when the attendant inserts plug P^2 into jack J^2 as will more fully hereinafter appear.

The release of relay 132 while relay 131 is operated causes the lighting of lamp 133 over a circuit including the left hand contact of relay 132, the right hand alternate contact of relay 132 the left-hand contact of relay 131 and the normal contact of relay 104, and the operation of relay 119 over a circuit including these same contacts. Relay 119, in operating, short circuits the polarized relay 107 in the same manner as hereinbefore described, thereby preventing the operation of the register 118 on an incoming call.

Upon noting the illumination of lamp 133, the attendant proceeds to answer the call by inserting plug P^2 into jack J^2 , whereupon the ringing response relay 130 is removed from the trunk and releases. The closure of jack contact 106 connects resistance 108 across the condenser in the central office side of repeating coil 100. This causes the operation of a relay in the ringing circuit which disconnects ringing current from the trunk in the manner set forth in the Newforth patent, supra. Upon the insertion of plug P^2 into jack J^2 , relay 104 operates as hereinbefore described. Relay 104 in operating, removes the locking ground from the winding of relay 131, whereupon relay 131 releases, opening the circuit for lamp 133. Lamp 133 thereupon extinguishes. Relay 104 in operating, connects ground to the right hand winding of relay 119, thereby maintaining this relay operated, so as to prevent the register 118 from operating during the established connection. Should the attendant on a disconnect signal withdrawn the plug P^2 from jack J^2 before the calling subscriber at B replaces the receiver on the switchhook, relay 120 will operate as hereinbefore described to maintain relay 119 operated and relay 107 short circuited, thereby rendering the register ineffective to register incoming calls.

From the above descriptions, it is apparent that applicant has devised a system wherein means are provided for discriminating between incoming and outgoing calls over a trunk circuit, whereby the message register associated with the trunk circuit is operated to register only those calls outgoing from the private branch exchange attendant's position and is rendered ineffective to register calls incoming over the trunk to that position. Furthermore, as hereinbefore described, false operation of the register, due to the intervention of attendants or to the actuation of the receiver hook by

either subscriber, is provided against at all times, no matter at what end of the line the call originates or terminates.

What is claimed is:

5. 1. In a telephone system, a two way trunk circuit a registering device therefor, and means including a polarized relay for rendering said device operable to register calls in one direction only, over said trunk.
  10. 2. In a telephone system, a telephone exchange, a two-way trunk circuit, a polarized relay, a registering device associated therewith, and means including a second relay for controlling said polarized relay for rendering said device operable to register only calls outgoing from said exchange over said trunk.
  15. 3. In a telephone system, a telephone exchange, a two-way trunk circuit, a polarized relay, a metering device associated therewith and means for controlling said relay for discriminating between calls incoming to and outgoing from said exchange over said trunk to selectively operate said device.
  20. 4. In a telephone system, a telephone exchange, a subscriber's station, means including a two-way trunk circuit and automatic switches for interconnecting said exchange and said station, a polarized relay, a registering device controlled thereby and means including a second relay for controlling said polarized relay whereby said registering device is actuated only upon an interconnection of said exchange and said station.
  25. 5. In a telephone system, a telephone exchange, a subscriber's substation, a two way trunk circuit and automatic switches for interconnecting said exchange and said substation, a registering device, and means including a polarized relay for rendering said registering device operable on a call originated at said exchange and inoperable on a call originated at said substation.
  30. 6. In a telephone system, a two way trunk circuit, a registering device therefor, and means including a polarized relay responsive to the seizure of said trunk at one end for causing said device to operate when a talking connection is established over said trunk, and means responsive to the seizure of said trunk at its other end prior to said first seizure for rendering said device inoperable.
  35. 7. In a telephone system, a telephone exchange, a subscriber's station, means including a two-way trunk circuit for interconnecting said exchange and said station, a polarized relay, a registering device, and means whereby said relay is controlled to actuate said device only once during each interconnection.
  40. 8. In a telephone system, a telephone ex-
- change, a subscriber's station, a two way trunk circuit and automatic switches for interconnecting said exchange and said substation, a registering device, means responsive to the establishment of a talking connection over said trunk circuit and said automatic switches for operating said device, said connection originating at said exchange, and means controlled by said device for rendering it inoperable until said connection is released at both ends.
9. In a telephone system, a telephone exchange, a subscriber's station, means including a two way trunk circuit and automatic switches for interconnecting said exchange and said station, a relay, means jointly controlled from said exchange and said station for operating said relay on a call originating at said exchange, means for rendering said relay inoperable on a call originating at said station, and a registering device controlled by said relay.
10. In a telephone system, a telephone exchange, a subscriber's station, means including a two way trunk circuit and automatic switches for interconnecting said exchange and said substation, a relay, means jointly controlled from said exchange and said substation for operating said relay on a call originating at said exchange, a second relay responsive to a call originating at said station for short circuiting said first relay, and a registering device controlled by said first relay.
11. In a telephone system, a telephone exchange, a subscriber's station, means including a two way trunk circuit and automatic switches for interconnecting said exchange and said substation, a polarized relay, means jointly controlled from said exchange and said substation for operating said polarized relay on a call originating at said exchange, a second relay responsive to a call originating at said station for short circuiting said polarized relay, and a registering device controlled by said polarized relay.
12. In a telephone system, a telephone exchange, a two way trunk circuit terminating therein, a subscriber's station, means including said trunk circuit for establishing a talking connection between said exchange and said station, a registering device, means responsive to the establishment of said connection for operating said device, and means for rendering said device inoperable should said connection be released and re-established at said exchange before its release at said substation.
- In witness whereof, I hereunto subscribe my name this 27th day of August A. D., 1923.

WALTER P. ALBERT
